METAL CASTING APPARATUS

Sam J. McCain, Fairmont, W. Va.

Application October 22, 1948, Serial No. 56,011

4 Claims. (Cl. 22—1)

1

This invention relates to an apparatus for separating the casting from the sand and the mold.

An object of the invention is the provision of a shake-out apparatus in which a pair of tracks guide carriages for supporting a shake-out device around an annular path where stations are indicated for performing a number of operations, one of the tracks having a short movable section adapted to be raised at the shake-out station when arms are elevated for tilting the usual mold board for separating the sand mold and casting from each other and from the mold board, the flask and mold board being held against displacement from the carriage during the dumping action.

A further object of the invention is the provision of a shake-out device for a molding apparatus in which the device is carried along an annular path when molding, pouring, cooling and shake out stations are established, the shake-out device including a post suspended from a carriage guided by a track outlining the path for supporting a hollow mold seat upon which is mounted a tiltable mold board, an elevated beam mounted on the post having springs depending therefrom for controlling oscillation of a frame rockable on the post and retained against movement by a latch which is released during the lifting of a means for tilting the mold board to dump the sand and casting therefrom while the flask is retained in position by chains depending from the frame.

The invention is best understood from a consideration of the following detailed description in connection with the accompanying drawings, nevertheless, it is to be understood that the invention is not confined to the disclosure but is susceptible of such changes and modifications as shall define no departure from the salient features of the invention as expressed in the appended claims.

In the drawings:

Figure 1 is a fragmentary side view in elevation of my mold shake-out apparatus,

Figure 2 is a top plan view of the apparatus with parts broken away,

Figure 3 is a fragmentary transverse vertical section taken along the line 3—3 of Figure 2,

Figure 4 is an enlarged fragmentary longitudinal vertical section taken along the line 4—4 of Figure 2 showing the mechanism for moving the shaker along a track,

Figure 5 is a view in perspective of the shaker mechanism in an operative position for dumping the casting,

2

Figure 6 is an enlarged fragmentary transverse vertical section through the hollow mold seat and showing the mold board in a dumping position,

Figure 7 is a section similar to that shown in Figure 6 but disclosing the mold board in an inoperative position on the mold seat,

Figure 8 is a bottom plan view of the board,

Figure 9 is a fragmentary horizontal section through the lifting means for a section of the track and the operating means for tilting the mold board.

Figure 10 is a side view in elevation of the lifting means in lowered position,

Figure 11 is the same side view of the lifting means in an elevated position, and

Figure 12 is a fragmentary vertical section of the lifting means taken along the line 12—12 of Figure 11.

Referring more particularly to the drawing, 15 20 designates a plurality of main posts arranged in a vertical plane running centrally of the mold shake-out apparatus. The posts are secured to the floor of a building or other support by angle irons 16 and are connected at the upper end 25 thereof to spaced auxiliary posts 17 by metal brace bars 18 adjacent the ends of the apparatus. Brackets 20 (Fig. 1) project upwardly from the posts 17 for rigidly supporting an upper track 21. The sides of the track are parallel and are connected together by horizontal bars 22 braced by strap irons 23 and 24 (Fig. 3) bolted to other auxiliary posts 17a located between the posts 17 which aid in carrying the curved ends of the track.

The track 21 is in the form of an inverted channel member which includes straight parallel portion 30 and 31 and curved end portions 32 and 33 (Fig. 2). Flanges 34 are turned inwardly from the lower edges of the side walls of the channel with the free edges of said flanges being spaced from each other. Said flanges form a track for carriages 35 and 35a for suspending a support 36 carrying a hollow mold seat 37. The carriage is attached to an endless chain 38 received within the annular track 21. A sprocket 39 driven by a shaft 40 projects through a slot 41 formed in the upper face of the track and operates the chain 38. A motor 42 revolves the shaft. The track 21 and the carriages 35 form, in effect, an overhead trolley.

The support 36 is suspended from the carriage 35 as shown in Figures 1, 3, 4 and 5. Each carriage includes a pair of parallel axles 45, a pair of rollers 46 for each axle with the axles being connected together by a rod 47. A metal strap 50

has a hook or eye at the upper end to receive the rod 47 and which eye is located midway between the pair of axles of each carriage. The lower ends of the straps are connected by bolts 51 to semi circular plates 52 which are bolted to opposite faces of the upper end of the support 36. The upper straight edges 53 of said plates ride in close association with the flanges 34 of the track 21. A series of rollers 54 are carried by shafts 55 to support the chain 38 beneath the sprocket 39 (Fig. 4). Such rollers may be spaced at intervals beneath the chain.

A beam 56 is secured rigidly intermediate its ends thereof at 57 on the vertical support 36 (Figs. 1 and 5). A bar 58 is rigidly secured intermediate its ends to the outer end of the beam. Expansion springs 59 are connected between the bar and a bar 60 forming the outer end of a frame 61 which includes side arms 62 joined at the inner free ends by a rod 63 received by a journal 64 in the support 36 for pivotally mounting said frame. Chains 65 are suspended in pairs from the ends of the bar 60 and are provided with hooks 66 for engagement with a mold board 67 or with a flask (not shown) for a purpose which will be explained presently. The frame 61 in effect is a lever.

A latching device generally designated by the numeral 70 includes an arm 71 pivoted at 72 on the bar 60 and is held in place against the support 36 by a guide 73. A bell-crank 74 is pivoted at 75 on the lower free end of the arm 71 and is provided with a latch 76 engaging a catch 77 on the support 36. An arm 78 of the bell-crank is connected by a spring 79 to a finger 80 having an angular extension 81 pivoted at 82 on the latch 76. A spring 83 connects said finger with the support 36 and tends to pull the free end of the finger downwardly against a lug or tripping device 85 on a cylindrical strut 86 for a purpose which will be described presently. However, it may be stated here that the springs 79 and 83 cause the latch 76 to be released readily to avoid friction during the dumping action.

In Figures 9 to 12 inclusive is illustrated a hydraulic jack for not only raising the cylinder 86 and the associated elements but for raising a section 90 of a track 91 which is located in a horizontal plane lower than the plane of the track 21 and which forms a guiding support for said cylinder. A piston rod 92 projecting vertically from a jack cylinder 93 has its upper end in engagement with the movable track section 90 which is connected at its ends to rods 94 movably mounted in vertically disposed guides 95 fastened to the floor of a building. The cylinder 93 is also mounted on the floor of the building and is connected to the guides by straps 96 braced by rods 97. A piston not shown is rigid with the lower end of the rod 92. The hydraulic jack is quick-acting and is supplied with fluid under pressure above and below the piston. The usual valves (not shown) for controlling the flow of the fluid are actuated by the operator.

The lower end of the cylinder 86 is closed and a compression spring 100 has its lower end seated on the bottom of said cylinder while the upper end is secured rigidly to the lower end of a rod 101 passing through the upper closed end 102 of the cylinder. The upper end of said rod (Figs. 1 and 5) is bolted to the inner end of the beam 56. Arms 103 extend laterally from said end of the beam to which are secured guide rods 104. A cross head 105 extends rigidly in opposite directions from the closed end 102 of the vertical

5 cylinder 86 and is provided with passages at the free ends thereof to receive the lower ends of the rods 104. Nuts 106 threaded onto the lower ends of the rods provide limit stops for downward movement of the strut 86 away from the beam 56. The arms 103 and 105 are in the same vertical plane.

Figures 5 to 8 inclusive illustrate in more detail the construction of the hollow mold seat 37 and the mold board 67. The mold seat has a rectangular bottom 110, parallel side walls 111 and 112 and parallel end walls 113. The lower end of the support 36 is secured to the side wall 111 by a U-shaped member 114 which is riveted or bolted to the support and to said side wall. The side wall has a pair of notches 115 deep enough to receive neatly intermediate portions of a pair of arms 116 which have the inner ends thereof rigid with the lower end of the cylinder 86. Each 15 of the end walls 113 are also provided with notches 117 and 118 to receive respectively the free ends of a pair of rods 119 and 120 carried by the mold board 67.

The mold board consists of a pair of metal plates which are connected together adjacent the ends thereof by angle irons 121. A reinforcing member 122 is riveted to the intermediate portions of said plates. The depending vertical flanges 123 of the angle irons are bored to receive neatly the rods 119 and 120. A cleat 124 is secured to the under face of the board 67 for engagement with the upper edge of the side wall 112.

The inner free ends of the arms 116 are in engagement with the under face of the mold board 67. Bearings 125 are disposed inwardly of the free ends of said arms and project downwardly therefrom. These bearings carry a rod 126 which runs longitudinally in the seat 37. A pair of tongs each having arms 130 and 131 have bearings on the opposite ends of the rod 126 so that the respective jaws 132 and 133 on the upper ends of the legs will clamp over the rod 119. The leg 130 of each pair of tongs is connected by a spring 135 to a pin 136 on the adjacent end wall 113 while a spring 137 connects the corresponding end of leg 131 to this pin.

A carriage 140 (Figures 1, 5 and 12) is secured to the bottom of the cylinder 86 below the connection between the radial arms 116 and said bottom. This carriage includes an inverted U-shaped member having inturned flanges 141 on the lower edges of the side walls of said U-shaped member. The inner edges of said flanges are spaced apart to clear the piston rod 92. Grooved rollers 142, Figure 12, mounted on vertical axles 143 carried by the top of the U-shaped member and the flanges 141 receive the flanged portions 144 of the movable section 90 and the track 91 as the cylinder 86 and the attached elements are carried around the annular track. While the section 90 of the track is raised and lowered each time the cylinder 86 reaches said section nevertheless, the flanges 144 of the section must align with the corresponding flanges of the track 91 when the carriage 140 continues its travel away from the hydraulic jack 93. Brackets 145 (Fig. 1) connected between the posts 17 and the lower track 91 support said track at spaced points.

In Figure 5, a special construction of reinforcement for the curved end portions of the upper track 21 is illustrated. In this arrangement a U-shaped member 148 has the free ends of its legs riveted or welded to intermediate portions of the bar 22 and suspended therefrom. The bridging portion 149 of the U-shaped member rests upon the beam

56 when the support 36 and associated mechanism is brought to the unloading station.

Referring more particularly to Figure 2, it will be seen that there are three stations at various points along the track 91. A pouring station 150 is located at one parallel side portion of the track. A pourer's platform 151 is at the pouring station which carries the operator at the same speed as the moving mold board 67. A cooling station 152 is disposed at a curved end of the track and the casting is cooled further when said casting travels from the cooling station along the other parallel side portion of the track to the dumping station 153. A molding station 154 is located between stations 152 and 153.

The operation of my apparatus is as follows: The chain 38 and likewise the carriage 35 and the elements supported thereby are driven at a predetermined speed by the sprocket 39. The pourer's platform 151 is driven at the same speed permitting the operator to pour the materials without requiring him to follow the moving mold board which carries the flask.

After the pouring operation, the carriage passes to the cooling station 152 when the usual weights are removed and the latching device 70 is connected with the catch 71 on the support 36. The hooks 56 are then attached to the flask. The carriage then moves to the shake-out station 153.

During the third step, the operator opens the controlling valve for the hydraulic jack 83, causing the movable section 90 of the track to be raised together with the carriage 140, cylinder 86 and the radial arms 116. As soon as the lug 85 on the cylinder trips the latch 76 from the catch 77 on the support 36 the springs 59 are released and lift the flask from the casting on mold board 67. The mold board 67 is tilted by the free ends of the arms as shown in Figure 5 whereby the casting and sand are discharged from the mold board. This operation separates the sand and casting from the flask and board. When the board 67 is tilted by the elevation of the arms 116, the springs 135 and 137 (Figs. 5, 6 and 7) pull the legs 130 and 131 towards each other causing the respective jaws 132 and 133 to close over the ends of the rod 119 and limit the upward movement of the inner edge of the board. These tong arms 130 and 131 cooperate with the cleat to prevent the unseating of the board from the hollow seat 37. When the free ends of the arms 116 are lowered as shown in Figure 7 the springs 135 and 137 are relieved of the tension to spread the respective legs 130 and 131 for releasing the pairs of jaws 132 and 133 from the ends of the rod 119.

What I claim:

1. Metal casting apparatus comprising an upper annular track, an annular lower track, means supporting said tracks in vertically spaced substantially parallel relationship, a trolley suspended from and movable around said upper track, a support suspended from said trolley, a hollow mold seat carried by said support, a tiltable mold board supported on said mold seat, a beam secured to said support above said mold seat and extending to opposite sides of said support substantially perpendicular thereto, springs suspended from said beam above said mold seat, chains suspended from said springs and connectible at their lower ends to a mold flask, said springs having a strength sufficient to lift a flask from said mold board, a link connected at one end to said chains, latch means releasably connecting the other end of said link to said support for holding said chains in lowered position with said

springs expanded, an upright member disposed adjacent and substantially parallel to said support, means slidably supporting the lower end of said upright member on said lower track for movement therearound, means slidably connecting said member at its upper end to said beam, a movable section in said lower track, a jack disposed below said movable section for elevating said movable track section and said upright member when said member is positioned over said movable section, means on said upright member engageable with said latch means to release said link from said support and free said springs to contract and lift a flask from a casting on said mold board when said upright member is elevated by said jack, and arms extending from said upright member under the adjacent side of said mold board for tilting said mold board when said upright member is elevated to thereby discharge a casting from the mold board.

2. Metal casting apparatus comprising a lower annular track, an upper annular track, means supporting said upper track above said lower track, a trolley suspended from said upper track and movable therearound, casting supporting and discharging means comprising a support suspended from the trolley, a mold seat carried by said support, a mold board tiltably mounted on said mold seat, springs suspended from said support above said mold seat, means suspended from the lower ends of said springs for connecting said springs to a flask supported on said mold board, latch means connected to said springs at the lower ends thereof and connectible to said support for releasably latching said springs in extended condition, an upright member positioned adjacent said support, means supporting the lower end of said upright member on said lower track for movement therearound, means slidably connecting the upper end of said upright member to said trolley means connected to said lower track for elevating said member to release said latch means from said support to thereby free said springs to contract and lift a flask from said mold board, and means extending from said member under the adjacent edge of said mold board for simultaneously tilting the latter to discharge a casting therefrom.

3. In continuous casting apparatus including a lower annular track, an upper annular track, means supporting said upper track above said lower track, and a trolley suspended from said upper track and movable therearound, casting supporting and discharging means comprising a support suspended from the trolley, a mold seat carried by said support, a mold board tiltably mounted on said mold seat, springs suspended from said support above said mold seat, means suspended from the lower ends of said springs for connecting said springs to a flask supported on said mold board, latch means connected to said springs at the lower ends thereof and connectible to said support for releasably latching said springs in extended condition, an upright member positioned adjacent said support, means supporting the lower end of said upright member on said lower track for movement therearound, said lower track having a vertically movable section therein, means connected to said movable section of the lower track for elevating said movable track section and said upright member, means on said upright member engageable with said latch means to release said latch means from said support to thereby free said springs to contract and lift a flask from said mold board, means

extending from said member under the adjacent edge of said mold board for simultaneously tilting the latter to discharge a casting therefrom, and means carried by said seat and engageable with said mold board to limit tilting movement of the latter.

4. Metal casting apparatus comprising an annular lower track having a vertically movable section therein, a jack disposed below said movable section for raising the latter, an annular upper track disposed above and substantially parallel to said lower track, a carriage supported on and movable around said lower track, a trolley suspended from and movable around said upper track, an elongated support secured at one end to said trolley and depending therefrom, a mold seat rigidly secured to said support near the lower end of the latter, a mold board pivotally mounted on said mold seat for tilting movement relative to said seat, a strut secured at 10 one end to said carriage and upstanding therefrom, a beam secured to said support adjacent said trolley and extending substantially perpendicular to said support above said strut, means slidably connecting the upper end of said strut to said beam and providing a limit stop for downward movement of said strut away from said beam, a compression spring acting between said beam and said carriage resiliently urging said carriage downwardly away from said beam, 15 tension springs suspended from said beam, strands suspended from the lower ends of said tension springs and engageable at their lower ends with a flask supported on said mold board for lifting such flask when said springs are free 20 25 30 35

to contract, a link connected at one end to the lower ends of said tension springs, a latch engageable between said link and said support for releasably holding said link in position to maintain said tension springs under tension, an abutment carried by said strut and engageable with said latch to release said link and free said tension springs for contraction when said carriage is on said movable lower track section and said strut is raised by operation of said jack, and an arm projecting from said strut and engaging said mold board to tilt the latter upon upward movement of said strut for dumping a casting from said mold board when said tension springs are freed to contract and lift a casting enclosing flask from the mold board, said compression spring being effective to restore said strut and said movable track section to their original position after said jack has been operated.

SAM J. McCAIN.
